UNITED STATES PATENT OFFICE

CORWILL JACKSON, OF CHICAGO, ILLINOIS

TAMPER

Application filed February 23, 1929. Serial No. 342,021.

The main objects of this invention are:
 First, to provide a tamper which is especially desirable for use in tamping gravel, cinders and other ballast commonly known 5 in railway parlance as light ballast.

Second, to provide a tamper which is easily manipulated and enables the performance of a large amount of work with a minimum of effort.

10 Objects relating to details and economies of my invention will appear from the description to follow. The invention is defined and pointed out in the claims.

A structure which is a preferred embodiment of my invention is illustrated in the accompanying drawing, in which:

15 Fig. 1 is a fragmentary view of a tamper embodying the features of my invention, parts being shown conventionally and without special regard to relative proportions.

20 Fig. 2 is an edge view of the blade-like tool, the resiliency or flexibility thereof being indicated by dotted lines.

Fig. 3 is a transverse section on line 3—3 25 of Fig. 1.

Fig. 4 is a perspective view of the tool tip or nose piece.

25 Referring to the drawing, the cylinder 1 is provided with air connections 2 and 3 at its ends. The valve mechanism is not illustrated.

30 The plunger 4 is reciprocated within the cylinder to deliver blows to the impact member 5 which constitutes a shank for the blade-like tool 6, this shank being longitudinally slotted to receive the tool, the tool being secured to the shank by means of the rivets 7.

35 The shank is formed of a relatively thin wide plate, being preferably upwardly tapered, the blade being of steel or other material possessing resiliency.

40 At its lower end the blade is concavely curved, as best shown in Figs. 2 and 3, and it is provided with a nose or tip piece 8 of relatively heavy material, this nose piece being channeled at 9 to receive the end of the blade, the arm 10 being substantially longer than the arm 11. Rivets 13 arranged 45 through the arm 10 and registering holes in

the blade secure the tip to the blade portion of the holder. This nose or blade tip provides an end face of substantial width, and at the same time permits lateral vibration of the blade as indicated by dotted lines in 55 Fig. 2.

The blade is preferably curved as indicated which adds to its efficiency in working material under a tie. The ballast may travel down on the front side of the blade 60 and is effectively guided to the point where it is to be tamped.

My improved tamper is especially desirable for the tamping of light ballast such as gravel, cinders and the like as distinguished 65 from what is commonly designated as heavy ballast such as crushed stone.

The tamper is light, may be easily handled and, as stated, is of large capacity; that is, it enables the performance of a large 70 amount of work with a minimum of effort.

Having thus described my invention, what I claim as new and desire to secure by Letters Patent, is:

1. In a tamping machine, the combination 75 of a cylinder, a plunger within said cylinder, a tool shank projecting into said cylinder to receive the impact of said plunger, an upwardly tapered blade-like tool of resilient material convexly curved at its lower end, and a detachable blade tip of substantially greater thickness than the blade having its forward edge inclined in both directions from a central point.

2. In a tamping machine, the combination 85 of a cylinder, a plunger within said cylinder, a tool shank projecting into said cylinder to receive the impact of said plunger, and an upwardly tapered relatively wide and thin tool of resilient material longitudinally and 90 transversely curved adjacent its lower end.

3. In a tamping machine, the combination 95 of a cylinder, a plunger within said cylinder, a tool shank projecting into said cylinder to receive the impact of said plunger, an upwardly tapered blade-like tool of resilient material, and a detachable blade tip of substantially greater thickness than the blade having its forward edge inclined in both directions from a central point. 100

4. In a tamping machine, the combination
of a cylinder, a plunger within the cylinder,
a tool shank projecting into the cylinder to
receive the impact of said plunger, and a
blade-like tool of resilient material and of
5 substantial width and curved at its outer end,
said blade being provided with a tip of sub-
stantially greater thickness than the blade.
5. In a tamping machine, the combination
10 of a cylinder, a plunger within the cylinder,
a tool shank projecting into the cylinder to
receive the impact of said plunger, and a
blade-like tool of resilient material and of
substantial width and longitudinally and
15 transversely curved adjacent its outer end.
6. In a tamping machine, the combination
20 of a cylinder, a plunger within the cylinder,
a tool shank projecting into the cylinder to
receive the impact of said plunger, and a
blade-like tool of resilient material and of
substantial width, said blade being provided
25 with a tip of substantially greater thickness
than the blade.
7. In a tamping machine, the combination
30 of a cylinder and coacting plunger, an impact
member operatively associated with said
plunger, and a blade-like tool mounted on
said impact member, said blade being curved
at its outer end and provided with a relative-
ly heavy tip.
8. In a tamping machine, the combination
35 of a cylinder and coacting plunger, an im-
pact member operatively associated with said
plunger, and a blade-like tool mounted on
said impact member, said blade being longi-
tudinally and transversely curved adjacent
its outer end.

In witness whereof I have hereunto set my
hand.
